UNITED STATES PATENT OFFICE.

JOHN E. OSTLINE, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed April 2, 1925, Serial No. 20,035, and in Great Britain April 24, 1924.

This invention relates to improvements in automatic or semi-automatic telephone systems and more particularly concerns arrangements for transmitting tones to an operator's position by giving special signals in the case of calls being set up to dead numbers or other numbers which for any reason are unattainable or set up to busy lines.

One feature of the invention concerns a novel arrangement for utilizing a tone current to bring about the intermittent operation of a supervisory signal. The particular advantage of this arrangement is that it is not necessary to make any alterations in the selectors, connectors or repeaters for transmitting an intermittent signal, such as a busy flash to an operator's position to indicate the busy or faulty condition of a line or switch.

Another feature of the invention concerns a novel arrangement for indicating to an operator the operated or non-operated condition of a device which connects up an impulse sender, the indicating device being also arranged to indicate the busy or faulty condition of a wanted line independently of the position of the key which connects up the impulse sender.

A further feature of the invention concerns an arrangement for intermittently operating a supervisory signal to indicate the busy or faulty condition of a line or switch by the connection of a booster battery potential to a speaking conductor at any stage of a connection, a tone current being superimposed on the speaking conductors to indicate whether the signal operated by the booster battery is being operated from a faulty or busy line; this arrangement has the advantage that no special trunk lines have to be provided for leading to operators' positions for dealing with such classes of calls.

A further feature of the invention relates to an improved impulse repeater having a polarized relay for responding to reversals of current and a non-polarized relay for responding to booster battery, the polarized relay being adapted to effect the operation of a supervisory relay to indicate the response of a wanted party and the non-polarized relay to indicate the busy or faulty

condition of a wanted line, the non-polarized relay being connected either in series or parallel with a winding of the polarized relay. 55

In order that the invention may be clearly understood and readily carried into effect a telephone system in accordance with the invention will be more fully described with reference to the annexed drawings which 60 show some examples of the invention.

Referring now to the drawings comprising Figs. 1-10, inclusive, these figures show sufficient of the circuits and apparatus of an automatic or semi-automatic telephone 65 system to enable the various features of the invention to be clearly understood.

Figs. 1 and 2 show a part of a telephone system comprising a manual exchange and an automatic exchange. More in detail, Fig. 70 1 shows the calling end of an operator's cord circuit O' terminating in the plug P'. Fig. 2 shows a trunk line extending from jack J in the manual exchange to the automatic exchange, terminating thereat in a selector 75 switch (not shown). Fig. 2 also shows the repeater MAR associated with the trunk line.

Figs. 3-8, inclusive, when placed in numerical order from left to right, show the principal switches used to extend a call from 80 an operator's position at a manual exchange to a subscriber in an automatic exchange.

More in detail, Figs. 3 and 4 show the apparatus at the manual exchange, which is 85 similar to that shown in Figs. 1 and 2.

Figs. 5 and 6 show apparatus located at an automatic exchange which is located between the manual exchange and another automatic exchange. The selector S, Fig. 5, 90 terminates the trunk from the manual exchange.

Fig. 6, shows an impulse repeater AAR associated with the trunk comprising conductors 279 and 280 which is accessible in the 95 banks of selector S and which extends to a second automatic exchange.

Fig. 7 shows apparatus located at the second automatic exchange. The trunk line comprising conductors 279 and 280 terminates in an incoming selector (indicated by the dotted rectangle) similar to selector S, Fig. 5. Since the functions of the incoming selector are identical to those of selector S,

Fig. 5, no further reference thereto will be made. The incoming selector has access to the final selector FS, shown in detail, which in turn has access to the subscribers' lines. 5 Fig. 8, directly below the final selector FS, shows the tone machine for giving busy and number unavailable signals.

Figs. 9 and 10 show or indicate the principal switches used to extend a call from a 10 subscriber at an automatic exchange to an operator's position at a manual exchange. More in detail, the rectangle C indicates a 15 subscribers' lines switch. The rectangle S indicates a first selector accessible in the banks of the line switch C. The repeater R³ is associated with a trunk accessible in the banks of the selector S. This trunk extends to a second automatic exchange terminating thereat in the incoming selector 20 S' indicated by a rectangle. The repeater R² is associated with a trunk accessible in the banks of the selector S and extending to the operator's position O³, terminating thereat in the jack J³, Fig. 10. The answering end 25 of a cord circuit terminating in the plug P³ is also shown.

A detailed description will now be given of the arrangement whereby the usual busy tone current is utilized to operate a relay 30 which in turn brings about the transmission of a busy flash signal to an operator's position, reference being had to Figs. 1 and 2. When the operator inserts the plug P' of the 35 manual to automatic repeater MAR, Fig. 2, sleeve relays 203 and 200 energize in series over the following circuit: earth, relay 203, sleeve of jack J', sleeve of plug P', normally closed contacts controlled by spring 213, normally closed contacts controlled by spring 40 214, relay 200 to battery. Relay 200, upon energizing, completes the following circuit for the supervisory lamp L², earth 217, 216, L², battery. Relay 203, upon energizing, 45 completes at armature 218 a circuit for slow relay 205 and at armature 219 completes the following loop circuit across conductors 228 and 229; conductor 229, armature 219 and its working contact, lower right hand winding of repeating coil R, winding I of the 50 shunt field relay SFR, upper right hand winding of repeating coil R to conductor 228. Slow relay 205, upon energizing, prepares at armature 220, a circuit for slow relay 204 and at armature 221 completes a 55 circuit for the polarizing winding II of the shunt field relay SFR and at the same time prepares a circuit for relay 206. Everything is now in readiness for the operator 60 to dial the wanted number, who connects up the impulse sender or calling device CD by actuating the dialling key DK. The operation of the dialling key DK substitutes the calling device CD for the sleeve relay 200 65 at spring 213 and spring 214 connects the

high speed "flicker" F in circuit with the sleeve relay 200 through resistance 212, while springs 215 earth the common conductor CC. The lamp L² is now very rapidly flashed by the "flicker" F and a tone current is connected to the operator's induction coil over conductor X by the operation of relay P which was energized by the closure of springs 215. 70

Assuming that the first digit in the wanted number is 5 the operator will dial the digit 5 which will produce five interruptions in the circuit of sleeve relay 203. Relay 203 will accordingly produce at armature 219 five interruptions in the circuit of the line relay 80 of the selector (not shown) connected across conductors 228 and 229. The first time relay 203 deenergizes it completes at armature 218 the previously prepared circuit for slow relay 204; slow relay 204, upon energizing, 85 provides a direct loop across conductors 228 and 229 for subsequent impulses, excluding the repeater R and the winding I of the shunt field relay SFR. Relay 204 also removes earth at armature 223 from one side 90 of the condenser 209. The selector (not shown) connected across conductors 228 and 229 responds in known manner to the impulses dialled and then automatically hunts for an idle line in the selected level. 95

Assuming that all the lines in the selected level are busy, the well known cam springs of the selector will be operated on the eleventh rotary step to connect a busy tone current to conductor 229. The busy tone current is arranged to have a frequency of about 400 to 500 cycles per second and this current operates the vibratory relay 207 as follows: conductor 229, armature 219, lower right hand winding of repeating coil R, armature 252 and its resting contact, armature 226 and its resting contact, vibratory relay 207, condenser 209 to earth at armature 223, of slow relay 204 which at this time is in a deenergized condition. The vibratory relay 207, upon energizing, removes the short circuit from relay 206 at armature 223, whereupon relay 206 energizes in the following circuit: battery, resistance 208, relay 206, working contact and armature 221 to earth. Relay 206, upon energizing, completes a locking circuit for itself at armature 225; at armature 226 opens the initial energizing circuit for vibratory relay 207 and at armature 227 connects interrupted battery over the following circuit to the operator's cord circuit O', Fig. 1. Earth, battery, slow speed interrupter I, resistance 210, working contact and armature 227, upper left hand winding of repeating coil R, tip of jack J', tip of plug P', relay 201 to earth. Relay 201 operates its armature 217 in accordance with the interruptions produced by the slow speed interrupter I and flashes the lamp L². The circuit of the lamp 130

L^2 at this time is, however, rapidly interrupted by the high speed "flicker" F , but nevertheless the comparatively slow interruptions of armature 217 gives a distinctive 5 busy signal to the operator. The busy tone current may, of course, be connected up at a second or subsequent selector or at a repeater or connector; these switches will have well known circuit arrangements for connecting 10 up a busy tone current which is arranged to operate the special alternating current or vibratory relay 207, whereby the connecting up of the busy tone current at any stage of 15 the connection causes a busy flash signal to be transmitted to the operator's position.

Assuming that a connection is established to the wanted party without encountering any busy outlets, then, when the wanted party answers, the direction of current flowing over conductors 228 and 229 will be reversed in known manner whereupon the shunt field relay SFR will energize and at armature 252 disconnect the vibratory relay 207 from the speaking circuit and at 25 armature 224 short circuit the condenser 209' whereupon the following loop circuit will be completed for relay 201: earth, relay 201, tip of plug P' , tip of jack J' , upper left hand winding of repeating coil R , armature 224 and its working contact, lower left hand winding of repeating coil R , ring of jack J' , ring of plug P' , retardation coil 202 to battery. Relay 201 accordingly energizes over this circuit and at armature 217 30 extinguishes lamp L^2 thereby indicating to the operator that the wanted party has answered. Should the operator neglect to restore the dialling key DK after the necessary series of impulses have been transmitted, the operated condition of the dialling key is indicated to the operator by the rapid "flickering" of the lamp L^2 brought about by the "flicker" F when the dialling key is in its operated condition and moreover the 35 tone current TC is connected to the operator's induction coil over conductor X whenever the dialling key is in an operated position. When the conversation is finished and the calling and called parties have replaced their receivers, the shunt field relay SFR will deenergize and open at armature 224 the circuit for relay 201. Relay 201 will deenergize and complete the circuit for lamp lamp L^2 , whereupon the operator will withdraw the plug from the jack J' , whereupon all energized relays in the manual to automatic repeater MAR will deenergize. 40

From the above arrangement it will be seen that a novel and useful arrangement has been provided for utilizing a busy tone current to give a flashing signal to an operator's position. The great advantage of such an arrangement is that standard 45 selectors, repeaters and connectors may be

used without providing special arrangements for repeating a busy flash signal to an operator.

A detailed description will now be given of the booster battery method of transmitting a 70 busy flash signal from any stage of the connection to an operator's position reference being had to Figs. 3-8, inclusive. The operator's cord circuit O^2 , Fig. 3, and the manual to automatic repeater MAR', Fig. 4, are identical with the cord circuit O' , and repeater MAR, Figs. 1 and 2, respectively, except that the relay 408 is connected in parallel with winding I of the shunt field relay 406, relay 408 responding only to a booster battery current. 75

For the purpose of this description it will be assumed that the operator at the cord circuit O^2 dials the digits 2, 3, 4, which will operate the selector S, Fig. 5, at the first automatic exchange and the connector FS, Fig. 7, at the second automatic exchange to establish connection with a wanted party. When relay 403 of the repeater MAR' energizes the following circuit will be completed 90 for relay 230 of the selector S, Fig. 5, battery, upper winding of relay 230, resting contact and armature 238, conductor 430, upper right hand winding of repeating coil R' , winding I of the shunt field relay 406 and relay 208 in 95 parallel, lower right hand winding of repeating coil R' , working contact and armature 419, conductor 431, armature 239 and its resting contact, normally closed eleventh step cam springs CS, lower winding of relay 230 100 to earth. Relay 230, upon energizing, completes the following circuit for slow release relay 231; earth, 240, 242, 231, battery. Relay 231, upon energizing, first earths the holding conductor 245 at armature 244 and 105 at the back contact of armature 243 opens a point in the circuit of release magnet 237 and at the front contact of this armature prepares the operating circuits. The first series of impulses will be repeated by relay 230 to the 110 vertical magnet 235 over armatures 242, 243, and relay 232 to the vertical magnet 235. Slow series relay 232 energizes in series with vertical magnet 235 and remains operated throughout the series of impulses. Upon the 115 first vertical step off normal springs 250 and 249 close, the former prepares a circuit for release magnet 237 and the latter completes the following circuit for stepping relay 233, battery, 233, 249, 246, 245, 244, earth. Relay 233, upon energizing, completes a locking 120 circuit for itself at armature 248 and at armature 247 prepares a circuit for the rotary magnet 236. At the end of this series of impulses relay 232 deenergizes and completes 125 the rotary magnet circuit at the normally closed springs controlled by armature 246, whereupon the hunting operation takes place in known manner.

Assuming that all the lines in the selected 130

level are busy, the cam springs CS and CS' will be operated on the eleventh rotary step. The spring CS' opens the circuit of switching relay 234 and springs CS connect the common 5 busy conductor B through resistance 251 to conductor 431. Conductor B is connected to a busy machine similar to the busy machine shown in Fig. 8, where it passes through the low resistance secondary winding of a busy 10 tone induction coil, similar to induction coil BI, to booster battery, and consequently a busy tone current and a booster battery current are superimposed on conductor 431. The busy tone current will not serve any useful purpose 15 in this connection, but the booster battery current will bring about the operation of relay 408 which as before mentioned only responds to an increased current. Relay 408, upon energizing, removes the short circuit 20 from relay 407 at armature 428, whereupon relay 407 establishes a locking circuit for itself at armature 426 and at armature 427 opens the initial energizing circuit of 408 and at armature 425 connects up interrupted 25 battery through the slow speed interrupter I', and resistance 409 to relay 401 of the cord circuit O², which flashes the lamp L³ in unison with the interrupters produced by the interrupter I'. 30 Assuming now that the selector S, Fig. 5, finds an idle line in the selected level and that this line comprises conductors 260 to 262, inclusive, under these circumstances no circuit will be completed for stepping relay 233 upon 35 the deenergization of slow relay 232, but instead the following circuit will be completed for switching relay 234; earth, 244, 245, CS', 234, 253, 249, 233 to battery. Switching relay 234 alone energizes in this circuit on account 40 of the high resistance of relay 234. Relay 234, upon energizing, switches the speaking conductors through to the conductors 260 and 262 at armatures 238 and 239, respectively. These conductors lead to the automatic to 45 automatic repeater AAR, Fig. 6, and at armature 241 the test wiper is connected to conductor 261. Relay 234 also at armatures 238 and 239 opens the circuit of relay 230 which in turn opens the circuit of release relay 231. 50 Switching relay 234, however, is maintained energized by release relay 231 until earth is fed back over conductor 261 which occurs in the following manner. 55 When the speaking conductors 430 and 431 are extended to conductors 260 and 262, respectively, relay 265 energizes over the following circuit; battery, upper winding of relay 265, normally closed contacts controlled by armature 267, conductor 260, armature 238 and its working contact, conductor 430, the loop circuit in the repeater MAR', conductor 431, armature 239 and its working contact, conductor 262, normally closed contacts controlled by armature 269, 60 normally closed contacts controlled by armature 268, and the lower winding of relay 265 to earth. Relay 265, upon energizing, completes a circuit for slow relay 263 at armature 273 and at armature 272 connects the following loop circuit across conductors 70 279 and 280 which lead to the final selector FS, Fig. 7, exclusive of resistance 274, Fig. 6; conductor 279, upper winding of relay 266, right hand winding of shunt field relay SFR', lower winding of relay 266, resting 75 contact and armature 271, working contact and armature 272 to conductor 280. Slow relay 263, Fig. 6, upon energizing, earths the release trunk conductor 261, at armature 278, thereby establishing the usual holding circuit for switching relay 234 of the selector S before the slow release relay 231 has had time to deenergize; at armature 276 completes a circuit for the polarizing winding of the shunt field relay SFR' and 80 at armature 277 prepares a circuit for slow relay 264. 85 When the previously traced loop circuit was completed across conductors 279 and 280, relay 283 energized in the circuit including the normally closed contacts controlled by armatures 294 and 295 of the back bridge or reversing relay 282. Relay 283, upon energizing, completes a circuit at armature 296 for slow release relay 284; relay 90 95 284 prepares the impulsing circuit at armature 299 and at armature 298 prepares a holding circuit and at armature 297 earths release trunk conductor 281 in order to mark the final selector FS engaged. The operator may now dial the next digit in the wanted number, whereupon the hereinbefore described results will take place in the manual to automatic repeater MAR', Fig. 4. At 100 the first interruption of the speaking conductors 430 and 431, the circuit of relay 265, Fig. 6, is opened. Relay 265 will open the circuit of relay 283, Fig. 7, at armature 272, and relay 283 transmits one impulse to the vertical magnet 291 in the following circuit; 105 earth, 296, 299, 326, 324, 285, 291, battery. Relay 265, Fig. 6, upon deenergizing in response to the first impulse will also complete the previously prepared circuit for relay 264. Relay 264, upon energizing, connects a direct loop across conductors 279, 280, excluding the winding of relay 266 and SFR'. Subsequent impulses to vertical magnet 291 are repeated by relay 283 and 110 relay 283 transmits them over the circuit: earth, 296, 299, 326, 327, 300, 285, 291, to battery. Off normal springs 324-327, inclusive, operate on the first vertical step and relay 285 energizes in series with the vertical magnet and remains energized 115 throughout the series of impulses. In response to this series of impulses the wipers 329 to 331, inclusive, are raised opposite to the third level of bank contacts. 120 125 At the end of this series of impulses relay 130

285 deenergizes and prepares at the back contact of armature 300 a circuit for rotary magnet 292, the next and last series of impulses dialled by the operator are repeated in the hereinbefore described manner, and relay 283 at armature 296 transmits the first impulse to the rotary magnet 292 over the following circuit: earth, 296, 299, 326, 327, 300, 328, 319, 292, to battery, and subsequent impulses over armature 316 of relay 289; the rotary magnet 292 rotates the wipers 329-331, inclusive, on to the fourth set of contacts in the third level, and slow relay 289 is energized in parallel with the rotary magnet over the back contact and armature 304 of relay 287 and remains energized during the transmission of this impulse series. Relay 289 at armature 316 closes the previously mentioned point in the impulsing circuit and at armature 315 completes a circuit for slow relay 288 as follows: earth, 315, 307, 288, battery; and at armature 314 opens a point in the circuit of switching relay 290. Relay 288, upon energizing, opens at armature 328 the path over which the first impulse was transmitted to the rotary magnet, at armature 312 connects the busy tone and booster battery conductor BT to armature 309 of relay 287 through resistance 323; at armature 311 prepares a locking circuit for itself and at armature 310 completes a circuit for the upper winding of two-step relay 287. Two step relay 287 being marginally adjusted only operates armature 308 in this circuit. Shortly after the termination of the final series of impulses to the rotary magnet 292, relay 289 deenergizes and opens at armature 315 the circuit for slow relay 288; at armature 314 closes a point in the circuit of switching relay 290 and at armature 313 closes a point in an alternative circuit of relay 288. If the wanted line is free there will be no earth potential on its test wiper 330 and switching relay 290 will energize over the following circuit: earth, 298, lower winding of switching relay 290, resting contact and armature 314, resting contact and armature 306, test wiper 330 through the cut off relay and driving magnet of the line switch (not shown) of the wanted party's line. Relay 290, upon energizing, completes a locking circuit for itself at armature 320; at the back contact of armature 321 opens a point in the circuit for fully energizing the two-step relay 287; at the front contact of the same armature short circuits its lower winding; and at armatures 317 and 322 connects the wipers 329 and 331, respectively, to a source of ringing current. The ringing current is fed over conductor 322 through the upper winding of ring cut off relay 286, resting contact and armature 301, working contact and armature 317 and wiper 329 to one side of the subscriber's line and returns

over the other side of the subscriber's line, wiper 331, armature 322 and its working contact, armature 303 and its resting contact to battery. The operation of the ringing current is fed back to the operator's position over armature 318 and its working contact and small capacity condenser c. 70

When the called party answers ring trip relay 286 operates, closes a locking circuit for itself at armature 302 and at armatures 75 301 and 303 completes the talking connection. A further result of the operation of relay 286 is the completion of the circuit for back bridge relay which energizes over the called subscriber's loop and reverses the direction of current over conductors 279 and 280 whereupon the shunt field relay SFR' in the automatic to automatic repeater AAR energizes in series with relay 266, but relay 266 being marginally adjusted does not energize at this time. 80

Relay SFR', upon energizing, reverses the direction of current over conductors 260 and 262 at armature 267 and 268, respectively, whereupon the shunt field relay 406 in the 90 manual to automatic repeater MAR' energizes and completes a circuit at armature 424 for relay 401 in the cord circuit O². Relay 401, upon energizing, opens the circuit for the supervisory lamp L³ thereby informing the operator that the called party has answered. 95

The operator will in the meantime have restored the dialling key DK', the lamp L³ having glowed steadily until the called party answered. Should the operator neglect to restore the dialling key DK a circuit will be completed for the lamp L³ through the "flicker" F' thereby guarding against the dialling key being left in its operated position. 105

When the conversation is finished and the called party replaces his receiver, the back bridge relay 282 deenergizes and restores the direction of current over conductors 279 110 and 280 to normal whereupon shunt field relay SFR' of the automatic to automatic repeater AAR deenergizes and reverses the direction of current over conductors 260 and 262, whereupon shunt field relay 406 in the 115 manual to automatic repeater MAR' de-energizes and opens a point in the circuit of relay 401 of the cord circuit O². Relay 401 upon deenergizing completes a circuit for the supervisory lamp L³ whereupon the operator 120 withdraws the plug P'' from the jack J'' bringing about the release of sleeve relay 403. Sleeve relay 403, upon deenergizing, opens the circuit of slow relay 405 at armature 418 and at armature 419 opens the 125 loop circuit extending over conductors 430 and 431, whereupon relay 265 in the automatic to automatic repeater, Fig. 6, de-energizes. Relay 265, upon deenergizing, opens the circuit of slow relay 263 at arm- 130

ture 273 and at armature 272 opens the loop circuit extending to the connector FS, Fig. 7. Slow relay 263, upon deenergizing, removes earth from release trunk conductor 261, whereupon selector S is released in known manner and in the final selector FS relays 283 deenergizes as a result of the loop circuit which opened at armature 272 of relay 265. Relay 283, upon deenergizing, opens the circuit of release relay 284 and relay 284, upon deenergizing, removes earth from test conductor 281 at armature 297 and at armature 298 removes earth from the local holding conductor; at armature 299 completes the following circuit for release magnet 293: earth, 296, 299', off normal springs 325, release magnet 293 to battery.

By the operation of the release magnet 293 the wipers 329-331, inclusive, are restored to normal, the off normal springs 325 opening the circuit of the release magnet in normal position.

Let us assume now that the line of the wanted party is busy when connection was established therewith. Under these conditions there is an earth potential on wiper 330 and switching relay 290 is short circuited upon the de-energization of slow relay 289. Shortly after the de-energization of relay 289, relay 288 de-energizes and removes the short-circuit from the lower winding of the two-step relay 287 at armature 310. Switching relay 290 being at this time de-energized the following circuit for fully energizing relay 287 is completed: battery, upper and lower windings of relay 287 in series, working contact and armature 308, resting contact and armature 321 to earth at armature 298. Relay 289 upon fully energizing operates its armatures 304, 305, 306, 307 and 309, and at armatures 307 and 306 completes the following circuit for relay 288: battery, 288, 307, normally closed contacts controlled by armature 311, 313, 306, test wiper 330 to earth. Relay 288, upon energizing, connects booster battery and busy tone to relay 266 of the automatic to automatic repeater Fig. 6, as follows: booster battery BB, Fig. 8, secondary winding of busy tone induction coil BI, conductor BT, working contact and armature 312, resistance 323, armature 309 and its working contact, conductor 280, armature 272 and its working contact, armature 271 and its resting contact, lower winding of relay 266, right hand winding of shunt field relay SFR', upper winding of relay 266, conductor 279, normally closed contacts controlled by armature 294, upper winding of relay 283, to battery an earth. Relay 266 alone energizes in this circuit and at armature 269 connects booster battery to relay 408 of the manual to automatic repeater MAR' Fig. 4, over the following circuit: booster battery,

resistance 270, armature 269 and its working contact, conductor 262, working contact and armature 239, conductor 431, armature 419 and its working contact, lower right hand winding of repeating coil R', armature 423 and its resting contact, armature 427 and its resting contact, relay 408, upper right hand winding of repeating coil R', conductor 430, armature 238 and its working contact, conductor 260, normally closed contacts controlled by armature 267, to the upper winding of relay 265 to battery and earth. It will be noted that winding I of relay 406 is in parallel with relay 408 but relay 406 of the shunt field type does not energize with increased current. Relay 408 upon energizing removes at armature 428 the short circuit from relay 407 and relay 407 brings about the transmission of interrupted battery to relay 401 which in turn flashes the lamp L³ in the manner previously described. The busy tone current is also transmitted to the operator over the speaking conductors and the operator is thus given a visual as well as an audible signal indicating that the wanted line is busy.

A detailed description will now be given of the operations which take place when a connection is established with an out of order or faulty line. When a faulty line is discovered or when any line is to be placed out of order, the exchange attendant removes the battery connection from the cut-off relay. Let us assume then that the final selector establishes a connection to a faulty line. Under these conditions neither battery nor earth will be found by the test wiper 330. When slow relay 288 de-energizes shortly after the de-energization of slow relay 289 it removes the short-circuit from the lower winding of the two-step relay 287 at armature 310 whereupon relay 287 energizes over both its windings in series and operates armatures 304, 305, 306, 307 and 309. Armatures 306 and 307 this time do not complete a circuit for slow relay 288 as there is no earth potential on wiper 330. Relay 289 will however energize again but its operation does not serve any useful purpose at this time. With relay 287 energized and relay 288 de-energized booster battery is connected to conductor 280 as follows: booster battery, Fig. 8, low resistance secondary winding of the number unobtainable tone induction coil NUI, tone conductor NUT, resting contact and armature 312, resistance 323, armature 309 and its working contact to conductor 280. Since the same booster battery is connected to conductor 280 the hereinbefore described operations will take place in the repeaters AAR and MAR' and the lamp L³ will be flashed as before, the tone current superimposed on the speaking conductors will however be characteristic of number unobtainable and the operator can

then inform the calling party that the wanted line is out of order.

A description of the number unobtainable and busy tone circuit will now be given reference being had to Fig. 8. X is a high speed interrupter and Y a slow speed interrupter. The slow speed interrupter Y is connected in circuit with the primary winding of the induction coil BI and the high speed interrupter in circuit with the primary winding of the induction coil NUI. One side of the low resistance secondary windings are common and connected to the booster battery BB while the other side of each secondary is connected to the common busy tone conductor BT, and the common number unobtainable tone conductor NUT, respectively.

A description will now be given of the repeater R³, Fig. 9, which may be taken into use either in a connection from an automatic exchange to a manual exchange or from a manual exchange to an automatic exchange, as well as in automatic to automatic exchange connections. In the first case it is very desirable that the calling subscriber can attract the operator's attention by slowly operating the switch-hook in the same way that an operator is signalled in a manual system. When this method is used in an automatic system, the slow operation of the switch-hook brings about the release of the switches involved in the connection and one feature of the repeater R³ is the provision of suitable holding arrangements which prevent the release of a connection while at the same time give switch-hook supervision. When the repeater R³ is taken into use in a connection between a manual exchange and an automatic exchange, it is very desirable that the busy or number unattainable condition of a wanted line or group of lines be indicated visually as well as audibly to the operator, and a further feature of the repeater R³ is the provision of suitable arrangements enabling the repeater to perform either of these functions dependent upon whether it is taken into use in a connection from an automatic exchange to a manual exchange or in a connection from a manual exchange to an automatic exchange. When the repeater is taken into use in an automatic to automatic interchange connection a relay in the repeater is adapted to respond to the closed condition of the wanted line and bring about the operation of the calling party meter. In order to explain the holding features with switch-hook supervision, a detailed description of a connection between an automatic subscriber and a manual operator will now be given with reference to Figs. 9 and 10. The reference character C indicates an automatic subscriber's rotary line switch of known type and the reference

character S indicates a first selector switch also of known type. The repeater R³ is the repeater previously referred to and S' a selector switch of known type similar to the selector switch S. The repeater R² and the operator's position O³ form no part of the present invention, and are shown in the present application in order that the holding feature of repeater R³ may be fully explained.

It is assumed that the subscriber whose line terminates in the line switch C desires to establish a connection with the operator's position O³, Fig. 10, and that the selector switch S' is taken into use by the repeater R₂. Under these conditions, relays 453 and 454 will energize in series over the normally closed contacts controlled by armatures 468 and 469 of the shunt field polarized relay 455 and the speaking conductors leading to the calling subscriber's station. Relay 453 upon energizing completes a circuit at armature 466 for slow release relay 450 and relay 454 completes a loop circuit across conductors 513' and 515' leading to the selector switch S'. Slow relay 450 upon energizing earths the release trunk conductor 471, thereby rendering the repeater R³ busy, and holding the switches S and C operated; at armature 461 prepares a circuit for slow relay 451 and at armature 462 completes an energizing circuit for the polarizing winding or relay 455. The double wound line relay (not shown) of the selector S' energizes over the following loop circuit which was completed at armature 467 by the operation of relay 454; battery, winding of line relay of the selector S', conductor 513', upper winding of marginal relay 456, right hand winding of shunt field relay 455, lower winding of relay 456, resting contact and armature 470, working contact and armature 467, conductor 515' to the other winding of the line relay of the selector S', and earth. The line relay of the selector S' alone energizes in this circuit and prepares the selector for operation in the usual manner. The shunt field relay 455 does not energize owing to the direction of current through its right hand winding and relay 456 being marginally adjusted only responds to a booster battery impulse which is connected to conductor 515' whenever the selector S' finds all lines of a group engaged. In the present case if the selector S' found all lines engaged, the operation of the marginal relay 456 would have no effect. Since the call originates in an automatic exchange the usual busy signal would be transmitted over the speaking conductors to the calling subscriber.

The calling subscriber may now dial the necessary series of impulses to operate the selector S'. Relays 453 and 454 respond to the interruptions produced by the calling device in transmitting this digit. Relay 130

454, upon deenergizing, opens the loop circuit extending over conductors 513' and 515', whereupon the line relay of the selector S' deenergizes and transmits one impulse 5 to the operating magnet. Relay 453, upon deenergizing, in response to the first impulse completes the previously prepared circuit for slow relay 451, and relay 451 at armature 464 completes a direct loop across conductors 513' and 515' excluding the windings of relays 456 and 455. Subsequent impulses are repeated over this direct loop circuit by the operation of relay 454. Relays 450 and 451 being slow to release re- 10 main energized throughout the transmission of impulses. The selector S' operates in known manner to select an idle trunk leading to the repeater R². At the end of the series of impulses transmitted to the selector S', slow relay 451 deenergizes and removes the direct loop from conductors 514' and 515' and when the selector S' finds an idle trunk which we will assume is the trunk comprising conductors 513 to 515, inclusive, 15 relays 516 and 517 energize over the following circuit: battery, winding of relay 516, conductor 513, conductor 513', upper winding of marginal relay 456, right hand winding of shunt field relay 455, lower winding 20 of relay 456, resting contact and armature 470, working contact and armature 467, conductor 515', conductor 515, winding of relay 517 to earth. Relay 517, upon energizing, completes a circuit for slow release 25 relay 518, and relay 516, upon energizing, connects the upper winding of relay 519 to the upper speaking conductor of repeater R² at armature 526, and at armature 525 opens a point in the locking circuit for relay 517. Slow relay 518, upon energizing, 30 earths release trunk conductor 514 at armature 528 to mark the repeater R² engaged and completes a holding circuit for the selector S' and at armature 530 connects artificial ringing induction to conductor 513 from the ringing tone machine RT and through the ringing tone condenser RTC in order that the calling party may receive 35 a ringing tone when dialling a manual exchange. At armature 529 relay 518 also completes the following circuit for the calling relay 520 at the operator's position O²: earth, lower winding of relay 519, working contact and armature 529, trunk conductor 530, armature 532 and its resting contact, winding of relay 520 to battery. Relay 520 energizes in this circuit but relay 519 does not energize over its lower winding on account of the high resistance of relay 520. 40 Relay 520, upon energizing, completes a circuit at armature 533 for the calling lamp CL. The operator, upon seeing the lighted condition of the calling lamp, inserts the plug P² into the jack J² whereupon a circuit is completed for relay 521 over the 45 sleeve of jack J², sleeve of plug P², relay 522 to battery. Relays 521 and 522 energize in series, the former opens the circuit of relay 520 whereupon the calling lamp CL is extinguished and the latter prepares 70 a circuit for the supervisory lamp SL at armature 534. When the plug P² was inserted in the jack J² the following circuit was also completed for relays 519, 523 and 524: earth, relay 523, tip of plug P², tip of jack J², conductor 531, armature 526 and its working contact, upper winding of relay 519 to battery; and earth, lower winding of relay 519, working contact and armature 529, conductor 530, ring of jack J², ring of 75 plug P², relay 524 to battery. Relays 519 and 523 energize over this circuit, the former disconnects the ringing tone from conductor 513 at armature 535, and at armature 536 prepares a locking circuit for relay 517 and the latter opens a point in the circuit of the supervisory lamp SL at armature 537. A connection is now completed to the operator who converses with the calling party and completes the connection in known manner. The polarized relay 455 in the repeater R² is not energized as no reversal has taken place over conductors 513' and 515'. 80

Assuming the calling party desires to attract the attention of the operator by slowly operating his switch-hook and thereby deenergizing relays 453 and 454 of the repeater R², relay 454 at armature 467 connects relays 452 to conductor 515', and at the same time 85 opens the loop circuit for relays 516 and 517 of the repeater R², relay 516 upon deenergizing closes a locking circuit for relay 517 at armature 525 over armature 536 and resistance 538 to battery. Relay 517, therefore, maintains slow relay 518 energized 90 which in turn holds the selector S' in an operated condition. The deenergization of relay 516 also at armature 525 connects battery over resistance 538, armature 536 and its working contact, resting contact and armature 525, conductor 515, conductor 515', armature 467 and its resting contact to relay 452 and earth. Relay 452, upon energizing, 95 earths the release trunk conductor 471, thereby maintaining the switches S and C in an operated condition, independently of the release relay 450, which relay will not fall away immediately upon the deenergization of relay 453, but will do so if the subscriber's loop is opened for a sufficiently long period, as 100 would occur by the slow operation of the switchhook. The continued slow operation of the switchhook will cause relay 516 to deenergize and energize in unison with the operation of the switchhook and at armature 105 526 it will open and close the circuit of relay 523, and relay 523 will intermittently operate the supervisory lamp SL, thereby drawing the operator's attention by the flashing of the lamp in a similar manner to the 110 115 120 125 130

flashing of a supervisory signal which takes place in an ordinary manual system. The operator, upon seeing the flashing supervisory lamp, will operate her listening key (not shown) and converse with the calling subscriber. From the foregoing it will be apparent that the release of the connection is under the control of the operator as relay 519 is energized over its lower winding in series with relay 523 at the operator's cord circuit. When the calling party hangs up, relays 452, 453, and 516 deenergize, and relay 516 at armature 526 opens the circuit for relay 523 which deenergizes and completes a circuit for the supervisory lamp SL which now grows steadily. When the operator gets the clearing signal from the called party she will withdraw the plug P^3 from the jack J^3 , whereupon relay 519 will deenergize and open the locking circuit for relays 517 and 452.

When the repeator R^3 is taken into use from a manual exchange, the busy flash feature is brought about in the same manner as described with reference to the automatic repeater AAR, Fig. 6, that is if the selector S' finds all lines of a group busy, it connects booster battery to conductor 515' which brings about the operation of marginal relay 456 and this relay in turn connects booster battery to a speaking conductor leading to the operator's position. If a connection is set up from an automatic subscriber in another exchange over the repeater R^3 , the operation of the shunt field polarized relay 455 will take place when the wanted party answers due to the reversal of current over the speaking conductors 513' and 515', and will reverse the direction of current over the speaking conductors leading to the calling subscriber and may be utilized to bring about the operation of his meter to register the call.

What I claim is:

1. In a telephone system, an operator's cord circuit for extending calls to called lines, a dialing key in said cord circuit for connecting an impulse sender to said cord circuit, a supervisory signal, means for operating said signal to indicate the busy or faulty, or idle condition of a called line, and means for operating said signal to indicate the actuated or deactuated condition of said dialing key.
2. In a telephone system, an operator's cord circuit for extending calls to called lines, a dialing key in said cord circuit for connecting an impulse sender to said cord circuit, a supervisory signal, means for operating said signal to indicate the busy or faulty, or idle condition of a called line, and means for operating said signal to indicate the actuated or deactuated condition of said dialing key, and means responsive to the actuation of said dialing key for connecting an audible tone to the operator's head set.
3. In a telephone system, an operator's position, means for extending a connection from said position via trunk lines in successive stages, means for sending current impulses back over the extended trunk line at any stage, and means at said operator's position responsive to the first of said current impulses for intermittently operating a supervisory signal at said operator's position.
4. In a telephone system, an operator's position, a trunk line comprising two inductively coupled sections, means for extending a connection from said operator's position via said trunk line, means for sending alternating current back over the outer section of said trunk line, a relay bridged across the outer section of said trunk line responsive to said alternating current, means controlled by said relay for sending an interrupted direct current over the inner section of said trunk line, and a supervisory signal at said operator's position responsive to said interrupted direct current.
5. In a telephone system, an operator's position, a cord circuit, a trunk line, means for extending a connection from said position via said cord circuit and said trunk line, a signal in said cord circuit, means for sending signalling current back over said trunk line apparatus for automatically and intermittently operating said signal, means for starting the operation of said apparatus responsive to said signalling current, said apparatus operating thereafter independently of said starting means.
6. In a telephone system, an operator's position, a trunk line, means for extending a connection via said trunk line to a called line in successive stages, means for causing a flow of current over said trunk line during the extension of said connection, means for changing the character of the flow of current over said trunk line at any stage in the extension of said connection, and means at said operator's position initially operative responsive to said change in the character of the flow of current over said trunk line for intermittently operating a supervisory signal at said operator's position, said last means operating thereafter independent of the character of current flow over said trunk line.
7. In a telephone system, means for establishing a connection from an operator's position to a called line, means for testing said line, means responsive to the finding of a busy or faulty condition of said called line for sending a signalling current over the talking conductors of said connection to operate a signal at said operator's position, and means responsive to the finding of a faulty condition for sending another signalling current over the talking conductors to operate said signal and to produce a tone in the operator's receiver.

8. In a telephone system, means including a trunk line for establishing a connection from an operator's position to a called line, means for testing said line, means operative when an abnormal condition of said line is found for superimposing one of two kinds of signalling current on the talking conductors of said trunk line, the kind of signalling current being determined by whether the 10 abnormal condition is a busy condition of the line or a faulty condition of the line.
9. In a telephone system, means for establishing a connection from an operator's position to a called line, means for testing said line, means operative when said line is found busy or faulty for sending a characteristic current over the talking conductors of said connection, means operative when the called subscriber responds for reversing the normal 20 current flow over the talking conductors of said line, a signal, a relay bridged across the talking conductors of said connection at said operator's position and responsive to said characteristic current for controlling said signal, and a second relay connected in parallel with said first relay responsive to reversal of current in said talking conductors for controlling said signal in a different manner.
10. In a telephone system, an operator's position, a trunk line, means for establishing a connection from said position via said trunk line to a called line, a signal at said position, a relay bridged across the conductors of said trunk line at said position operative in response to the removal of the receiver at the called station for operating said signal, and a second relay connected in parallel with said first relay responsive to the finding of the called line busy for operating said signal in a different manner.
11. In a telephone system, a repeater, a polarized relay and a marginal relay bridged across the talking conductors of said repeater, means for controlling both relays over the outgoing side of said repeater, and a signal controlled differently by each of said relays.
12. In a telephone system, means for establishing connection from an operator's position to a called line, means responsive to the busy condition of the called line for altering the character of the normal current flow over the talking conductors of said connection, means responsive to the removal of the receiver at the called station for reversing the normal current flow over said talking conductors, a non-polarized relay at said operator's position responsive to said altered current flow for operating said 50 a signal to indicate the busy condition of the called line, and a polarized relay at said operator's position responsive to said reversed current flow for operating said signal to indicate the response of the called subscriber.
13. In a telephone system, automatic switches in an automatic exchange, a repeater in said automatic exchange, an operator's position in a manual exchange, means for establishing a connection from a substation via said automatic switches and said repeater and interconnecting trunk lines to said operator's position, a line relay in said repeater, and a second relay in said repeater for connecting a holding potential on 70 the release conductor of said trunk lines, said second relay being jointly controlled by said line relay and the operator at said position.
14. In a telephone system, a repeater 80 adapted to be used in a trunk line for establishing a connection from a substation in an automatic exchange to an operator's position, or in a trunk line for establishing a connection from an operator's position to a substation in an automatic exchange, means in said repeater operative responsive to the replacement of the receiver at the substation for maintaining the connection intact and for signalling the operator when 85 said repeater is used in a connection of the first type, and means in said repeater for increasing the normal current flow over the connection when a busy or faulty condition is encountered on the line to the substation to operate a signal at the operator's 90 position when said repeater is used in a connection of the second type.
15. In a telephone system, means including a link circuit for extending a connection, a calling device, means for connecting said calling device with said link circuit, a signal, means responsive to the encountering of a particular condition during the extension of the connection for controlling the 100 operation of said signal, and means for controlling the operation of said signal to indicate when said calling device is connected to said link circuit.
16. In a telephone system, a calling device, means including trunk lines for extending a connection in successive stages by operating said calling device, means for distinctively marking a trunk line at any stage, a signal, and means responsive to a trunk 110 line being marked for operating said signal when said calling device is being operated.
17. In a telephone system, means including trunk lines for extending a connection in successive stages, means for applying a characteristic potential to a conductor of a trunk line at any stage, a signal, and means immediately responsive to said application at any stage for intermittently operating said signal.
18. In a telephone system, trunk lines, means for serially connecting said trunk lines to extend a connection, means for applying a characteristic potential to a conductor of any trunk line, and means associ- 120 125 130

- ated with the first trunk line and initially responsive to said application to a conductor of any trunk line for applying a different characteristic potential to a conductor of the 5 first trunk line, said last means operating thereafter independent of the potential on said conductor.
19. In a telephone system, means including trunk lines for extending a connection 10 in successive stages, means for applying a characteristic potential to a conductor of a trunk line at any stage, a signal, and means initially responsive to said application at any stage for operating said signal, said last 15 means operating thereafter independent of the potential on said conductor.
20. In a telephone system, a trunk, a line, means including an automatic switch for extending a connection from said trunk to 20 said line, means in said switch for applying a characteristic potential to a conductor of said trunk providing the line is busy, and for applying a different characteristic potential to a conductor of said trunk providing 25 the line is faulty.
21. In a telephone system, a line, means including a trunk for extending a connection to said line, a polarized relay and a marginal relay bridged across the conductors of said trunk, means for causing the 30 operation of said marginal relay operative providing the line is in a particular condition when the connection is extended thereto, means for causing the operation of said polarized relay when the call is answered, 35 and a signal controlled differently by said relays.
22. In a telephone system, a line, an automatic switch for extending a connection to said line, a test relay in said connector for 40 connecting either one of two characteristic potentials to a talking conductor of said connector, and means operative, providing the line is busy when connection is extended thereto, for determining which of said two 45 characteristic potentials will be connected to said conductor.

In witness whereof, I hereunto subscribe my name this 16th day of March, A. D. 1925.

JOHN E. OSTLINE.
